UNITED STATES PATENT OFFICE.

EDWARD C. MEAD, OF ELKHART, INDIANA.

WRENCH.

SPECIFICATION forming part of Letters Patent No. 445,185, dated January 27, 1891.

Application filed November 19, 1890. Serial No. 371,940. (No model.)

To all whom it may concern:

Be it known that I, EDWARD C. MEAD, a citizen of the United States of America, residing at Elkhart, in the county of Elkhart 5 and State of Indiana, have invented certain new and useful Improvements in Wrenches, of which the following is a specification.

My object is to increase the capacity of wrenches by providing means for giving wide 10 ranges of adjustment for different kinds of work.

The invention includes a ratchet-wheel carrying adjustable gripping-jaws and combined with two pawls which are adjustable 15 into and out of engagement with the ratchet, so that the same may be worked in either direction, left entirely free, or held rigidly to the handle.

In the accompanying drawings, Figure 1 is 20 a side elevation of the wrench partly in section. Fig. 2 is a sectional view on line *xx* of Fig. 1.

In the drawings, A is the body or framework of the wrench, having a hollow head *a*, 25 which is formed on one side with an inwardly-projecting annular flange. Within this head the ratchet-wheel B fits, and the teeth of this wheel project from the periphery, to be engaged by pawls C C', pivoted in recesses on opposite edges of the frame and operating in reverse direction. Each pawl has an inwardly-bent end *c*, and a spring 2, held 30 in the frame, is arranged to press these ends outwardly to make the other ends engage normally with the ratchet-teeth. The bent 35 ends are also acted upon by detents 3, pivoted within the recesses. These detents have cam-surfaces 4 and finger-pieces 5, and when they are turned so that the cam parts bear upon 40 the bent ends of the pawls they will be forced inward and held against the pressure of the spring, and the other ends will be held out of engagement with the ratchet. It will be seen from this arrangement that either pawl 45 may be held inoperative, or both may be disengaged from the ratchet, or both may engage the ratchet to hold the same rigid. In this way the ratchet may be rotated in either

direction, allowed to be free, or held rigid. The ratchet is held within the hollow head 50 by a cap or ring D, which has a flange adapted to bear upon the face of the head, and a threaded flange 6, engaging a thread cut within the head. The inner face of this flange bears against the sides of the projecting teeth. The ratchet is provided with a central recess of oblong form, and within this are fitted the adjustable jaws E. These jaws have grooves in their edges fitted to feathers projecting from the sides of the recess, and 60 upon these the jaws slide when adjusted. They are peculiarly notched, as shown, one end of each being cut away, as at 7, so that the adjacent end of the opposing jaw overlaps in order to secure a wider range of adjustment by permitting the jaws to move closer together and make the opening 65 smaller. The jaws are adjusted by thumbscrews F, the threaded shanks of which extend into the jaws. These screws are held 70 by pins *f*, projecting from the ratchet at the ends of the recess upon which the nuts turn. Only one recess is formed in the ratchet, all the described parts being located therein.

I claim as my invention—

1. In combination, the frame having the hollow head, the ratchet located therein and carrying the gripping-jaws, and the pawl for operating the ratchet, pivoted to the frame, the said head having a flange on one side 80 for retaining the ratchet in place and a ring-cap on the other removably secured to the head.

2. In combination, the hollow head having a flange on one side, the ratchet within the 85 head, the ring-cap having an inwardly-projecting flange screw-threaded into the head, and a suitable operating-pawl for the ratchet, substantially as described.

3. In combination with the head and pawl, 90 the ratchet having a recess, the jaws arranged to be adjusted therein, the means for moving them, the said jaws having overlapping projections, substantially as described.

4. In combination with the head and pawl, 95 the ratchet having a recess, the jaws arranged

therein, the thumb-nuts having screw-threaded shanks engaging the jaws, and the pins *f*, on which the nuts turn, said parts being within the recess, substantially as described.

5 5. In combination, the head, the ratchet, and gripping-jaws, the pawl pivoted to operate reversely upon the ratchet, the springs, and the pivoted detents for holding the pawls

out of engagement with the ratchet, substantially as described.

In testimony whereof I affix my signature in presence of two witnesses.

EDWARD C. MEAD.
